UNITED STATES PATENT OFFICE

136,021

DESIGN FOR A COMBINED FILTER AND STRAINER

Frederick Kraissl, Jr., North Hackensack, N. J.

Application November 25, 1942, Serial No. 108,876

Term of patent 7 years

To all whom it may concern:

Be it known that I, Frederick Kraissl, Jr., a citizen of the United States of America and resident of North Hackensack, in the county of Bergen and State of New Jersey, have invented a new, original, and ornamental Design for a Combined Filter and Strainer, of which the following is a specification, reference being had to the accompanying drawing forming part thereof.

The figure is a perspective view of a combined filter and strainer showing my new design. The rear side is substantially like the front side with the exception that the inlet port in the center portion is omitted.

I claim:

The ornamental design for a combined filter and strainer, as shown and described.

FREDERICK KRAISSL, JR.
